US0D1056002S

(12) **United States Design Patent** (10) Patent No.: **US D1,056,002 S**
(45) Date of Patent: ** Dec. 31, 2024

(54) **PRINTER**

(71) Applicant: **Shenzhen Anker Smart Technology Co., Ltd**, Shenzhen (CN)

(72) Inventors: **Mingshan Wang**, Shenzhen (CN);
Shenghui Jia, Shenzhen (CN)

(73) Assignee: **Shenzhen Anker Smart Technology Co., Ltd**, Shenzhen (CN)

(**) Term: **15 Years**

(21) Appl. No.: **29/865,987**

(22) Filed: **Aug. 23, 2022**

(30) **Foreign Application Priority Data**

Feb. 23, 2022 (CN) 202230088313.2

(51) **LOC (14) Cl.** **15-09**

(52) **U.S. Cl.**

USPC **D15/122**

(58) **Field of Classification Search**

USPC D15/122, 138, 141, 199; D18/50, 53, 56

CPC B29C 64/118; B29C 64/20; B33Y 70/00;

B33Y 70/10; B33Y 10/00; B33Y 30/00

See application file for complete search history.

(57) **CLAIM**

The ornamental design for a printer as shown and described.

DESCRIPTION

FIG. 1 is a front perspective view of a printer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the remainder of the printer form no part of the claimed design.

1 Claim, 7 Drawing Sheets
